SECURITY MEANS FOR CLOSURE CABINETS

Harry C. Miller and James L. Taylor, Rochester, N. Y., and Howard M. McCoy, Severna Park, Md.

Application September 19, 1956, Serial No. 610,758

5 Claims. (Cl. 312—297)

The present invention relates in general to file cabinets and like protective receptacles for valuables, and more particularly to multidrawer file cabinets having disappearing protective curtain or shielding means and cooperating combination lock mechanism.

Maintenance of proper security with respect to valuable papers and writings, which are normally housed in multidrawer file cabinets when not in use, requires, as a practical measure, the provision of some facility for locking the file cabinet drawers in closed condition in order to preserve the contents and secrecy and protect them from unauthorized inspection when the premises are unoccupied. The most conventional expedient for accomplishing this has been by adaptation of the file cabinet to receive a locking bar or the like which is padlocked to the frame in a position to retain the file cabinet drawers in closed position. Usually, vertically aligned fixed hasps or staples are provided at spaced locations on the front of the file cabinet, usually on the bottom horizontal frame member and an intermediate horizontal parting strip, into which the elongated steel locking bar of approximately the height of the front face of the file cabinet is inserted when the drawers are in closed position to overlie the drawer fronts. The bar is usually provided with an aperture adjacent the upper end thereof through which another hasp or staple fixed at the upper end of the file cabinet is projected to receive a padlock, or the bar is provided with a rearwardly offset flange which is apertured to receive a like hasp or staple projecting from the top wall of the cabinet. Numerous practical disadvantages attend this arrangement. The total exposure of the bars at the exterior of the file cabinet renders them readily subject to tampering by unauthorized personnel. The necessity of wholly removing the bars from the cabinet and storing them in out-of-the-way places while the file cabinets are in use during working hours presents space and storage problems, and the assembly and disassembly of such bars in locking position on the file cabinet are time-consuming procedures.

Resort has also been had to providing internal locking linkages whereby a control lever manipulated by an axial and reciprocable cylinder of a cylinder lock mounted in the front wall of the file cabinet controls a vertical link housed within the cabinet for depressing lock levers which cooperate with keeper mechanisms on each of the file cabinet drawers to release the levers from locking relation with the drawers. Such internal lock linkage mechanisms, however, significantly increase the complexity and cost of production of the file cabinet, and due to the very exacting tolerances which must be observed, in order to maintain effective high security operation of the locking mechanism over long periods of time, and the continual wear to which the cooperating locking parts are subjected, the degree of security which may be realized over long periods of time is not up to desired standards.

An object of the present invention, therefore, is the provision of a novel security file cabinet construction which may be readily conditioned in a very short period of time to protect the contents against unauthorized inspection or surreptitious entry into the cabinet.

Another object of the present invention is the provision of a novel security file cabinet construction having means incorporated in the file cabinet which may be readily disposed in a concealed position therein or positioned to bar

2

access to the file cabinet drawers in a novel manner whereby a high degree of security against unauthorized inspection of the contents may be realized over long periods of time.

Another object of the present invention is the provision of a novel multidrawer security file cabinet which may be readily locked by a simple padlock to preserve the contents of the file cabinet drawers against inspection, having improved efficiency and security characteristics.

Other objects, advantages and capabilities of the present invention will become apparent from the following detail description, taken in conjunction with the accompanying drawings illustrating two preferred embodiments of the invention.

In the drawings:

Figure 1 is a perspective view of the file cabinet constructed in accordance with the present invention;

Figure 2 is a fragmentary vertical section view taken along the line 2—2 of Figure 1, illustrating the file cabinet in locked condition;

Figure 3 is a vertical section view taken from the same section plan as Figure 2, but illustrating the file cabinet in unlocked condition;

Figure 4 is a horizontal section view taken along the line 4—4 of Figure 2;

Figure 5 is a fragmentary vertical section view illustrating the manner in which the curtain controlling slide is movably supported in the file cabinet, taken along the line 5—5 of Figure 1; and

Figure 6 is a fragmentary vertical section view through the curtain controlling slide and file cabinet front parting plate of a modified form of the present invention adapted for use with exposed shackle padlocks.

Referring to the drawings, wherein like reference characters designate corresponding parts throughout the several figures, and particularly to Figures 1—5, inclusive, showing the first embodiment of the present invention, the present invention is incorporated in a file cabinet, generally indicated by the reference character 10 which is of the multidrawer type having preferably an even number of file cabinet drawers such as, for example, the four drawers 11, 12, 13 and 14, illustrated in Figure 1. The drawers 11—14 are arranged in a vertical tier and each are preferably of conventional construction including a rectangular drawer front 15 having the usual drawer pull 16 projecting forwardly therefrom. The drawers are suitably supported in accordance with conventional practice for rectilinear horizontal movement between a closed position wherein they are completely housed within the file cabinet 10 between the side walls 17, 18 rearwardly of the cabinet front 19 and an exposed position wherein a major portion of the drawer projects forwardly of the cabinet front 19. The side walls 17, 18, the top wall 20 and the rear wall 21, are preferably formed of sheet metal in accordance with conventional practice, and reinforced in the usual manner to provide suitable rigidity. The cabinet front 19, however, comprises a rectangular marginal frame formed by vertical side rails 22 and 23 lying at the lateral corners of the cabinet front 19 adjacent the forward end of the side walls 17, 18 and top and bottom transverse marginal rails 24 and 25, respectively. An intermediate transverse parting plate 26 extends between and is rigidly secured to the side rails 22, 23 and is disposed in parallelism with the top and bottom rails 24, 25 spaced equally from the top and bottom rails. All of these rails 22—25 and the plate 26 lie in a vertical plane and define an upper rectangular opening 27 and a lower rectangular opening 28 in the cabinet front 19 for movement of the drawers 11—14 therethrough to and from closed position.

Rearwardly spaced from the vertical plane of the rails 22—25 and intermediate parting plate 26 is a secondary

frame 29 which likewise is disposed vertically and is provided with rectangular openings 30 into which the drawer fronts 15 are adapted to be received in flush coplanar relation with the secondary frame 29 when the drawers are in closed position. Between the in-turned flanges 22', 23' of the vertical rails 22, 23 and the forward edges of the secondary frame 29, there are provided a pair of inwardly opening C-shaped channel members 31, 32 disposed behind the upper opening 27 and a pair of inwardly opening C-shaped channels 33 and 34 located behind the lower rectangular opening 28. The pair of upper channels 31, 32 form a guide track for a metallic closure curtain 35 for the upper opening 27 and the channels 33, 34 form guide tracks for a metallic closure curtain 36 for the lower opening 28. Each of the channels 31-34 comprises a web 37 affixed to the adjacent side wall of the cabinet, channel sides 38 projecting perpendicularly inwardly from the adjacent cabinet side walls, and terminal flanges 39 defining a restricted opening to the channel. The channels are bent at right angles along a smooth curve as indicated at 40 at substantially the longitudinal center of each channel and are affixed to the cabinet side walls 17, 18 in a position to provide a vertical leg 41 opening immediately rearwardly of the side rail flanges 22', 23' and a horizontal leg 42 extending rearwardly to the rear wall 21 of the cabinet with the boundary of the channel opening at the uppermost channel flange 39 lying substantially in horizontal alignment with the upper edge of the intermediate parting plate 26. It will be noted that the vertical legs 41 of the upper channel tracks 31, 32 rise vertically from a location adjacent the upper edge of the intermediate parting plate 26 and the vertical legs 41 of the lower channel tracks 33, 34 depend from a region adjacent the lower edge of the intermediate parting plate 26.

The closure containers 35, 36 are each formed of narrow transverse slats 43 preferably formed of a hard sheet metal which will substantially resist tampering in attempts to penetrate the same, the opposite lateral marginal edges of each of the slats 43 being provided with substantially cylindrically curved flanges 44 curved about axes parallel to the longitudinal axes of the slats and opening in opposite directions whereby the ends of the curved flanges 44 of each pair of adjacent slats 43 may be interfitted with each other to permit pivotal movement of the slats relative to each other about their interconnected flanges 44. Suitable rods 45 are suitably secured to the opposite ends of each slat 43 or selected spaced slats 43 forming the curtains 35, 36 and project into the channel tracks 31-34 to be guided thereby. If desired, suitable rollers or enlarged washers 46 may be provided on the ends of the rods 45 to relieve friction between the rods and the channel tracks and restrain lateral movement of the curtains. Cap and base channels 47 are secured transversely of the cabinet at the upper and lower ends of the vertical legs 41 of the channel tracks to form seating recesses for the curtains 35, 36 when the same are in closed position covering the openings 27, 28.

In the preferred embodiment of Figures 1-5, a high security combination lock 48 is supported centrally on the intermediate parting plate 26 to lock the closure curtains 35, 36 in closing position. The combination lock 48, in the illustrated embodiment, is of the type comprising a plurality of coaxial rotary tumbler disks and driving cam housed within a lock casing 49 mounted on the rear face of the intermediate parting plate 26 and having a reciprocable bolt 50 projectable therefrom along an axial parallel to the longitudinal axis of the plate 26, together with dial assembly 51 including a dial and knob 52 connected with the mechanism in the casing 49 by means of a spindle for manipulating the tumblers and driving cam to effect withdrawal of the bolt 50 from its normally projected condition when locked. A curtain controlling slide member 53 extends

transversely of the cabinet immediately behind the intermediate parting plate 26 and is substantially coextensive in length with the plate 26. The slide member 53 preferably is formed of a channel-shaped member having horizontally disposed channel sides 54 and is arranged to accommodate the lock casing 49 therebetween when the slide member 53 is drawn to its forwardmost position as illustrated in Figure 2. This may be accomplished by disposing the web 55 of the channel forming the slide 53 forwardly and forming an aperture 56 therein of sufficient size to accommodate the lock housing 49, or by positioning the web of the channel rearwardly so that the channel faces forwardly to receive the lock housing 49 therein. In the embodiment illustrated in Figure 2, wherein the channel web 55 is disposed forwardly, a secondary channel member 57 is seated between the channel sides 54 with its web disposed rearwardly and is welded or otherwise rigidly secured to the slide channel 53. The secondary channel 57 has, in addition to the horizontally arranged upper and lower channel sides 58, opposite channel ends 59 whereby it cooperates with the primary slide channel 53 to form a protective enclosure for the sides and rear cover plate of the lock casing 49 to resist tampering with the lock housing. In this embodiment, a keeper block 60 is welded to one of the secondary channel ends 59 as illustrated in Figure 4 which presents a shoulder to the lock bolt 50 when the bolt is in projected position to prevent movement of the slide 53 rearwardly of the intermediate parting plate 26. To effect reciprocative sliding movement of the slide member 53 along a horizontal axis from the front to the rear of the cabinet, a pair of elongated inwardly opening channel tracks 61 are affixed to opposite side walls 17, 18 of the cabinet 35 between the horizontal legs 42 of the upper and lower channel tracks 31-34, to receive between their channel sides projecting stub shafts or trunnions 62 fixed and projecting oppositely from the end walls 63 of the slide channel member 53. The ends of the shafts or trunnions 62 may either be integral formations designed to snugly nest within the channel tracks 61 or may be provided with rollers or the like for relieving friction between the relatively movable members. A pair of such stub shafts or trunnions 62 which are in horizontal alignment with each other are preferably provided on each end wall 63 to resist canting movement of the slide 53.

Anchoring straps 64 of substantially the width of the slats 43 have cylindrically curved flanges 65 adapted to interlock with the lower flange 44 of the lowermost slat of upper curtain 35 and the upper flange 44 of the uppermost slat of lower curtain 36 to interconnect the closure curtains with the slide 53 and simultaneously control their movement from the slide.

In the embodiment shown in Figures 1-5 the slide 53 is reciprocated manually by means of a disconectable tubular rod 66 having a knurled head 67 projecting through a suitable aperture in the intermediate parting plate 26 to an exposed position forwardly of the parting plate. The tubular rod 66 is guided for rectilinear reciprocative movement by a guide rod 68 affixed to the rear wall 21 of the cabinet and telescoped into the tubular rod 66. The rear end of the control rod 66 carries a radially projecting disk sector 65 having a circumferential groove 70 therein of suitable width to accommodate a tongue 71 bounding a portion of the aperture 72 in the web 55 of the slide channel 53. The aperture 72 is over the major portion of its circumference of corresponding cross-section to the tubular control rod 66 and is provided with a relieved portion 73 over a portion of its circumference to accommodate the disk section 69 on the control rod 66.

In the use of the above-described embodiment, assuming the drawers to be in closed position, as illustrated in Figure 2, with the closure curtains 35-36 in

closed condition and the lock 48 in locked condition, the cabinet is unlocked and opened for use by manipulating the dial knob 52 to establish the combination and actuate the tumblers to withdraw the bolt 50 from behind the keeper block 60. The tubular control rod 66 is then withdrawn outwardly of the file cabinet to draw the disk sector 69 into registry with the aperture 72 in the web 55 of the slide 53 with the disk sector 69 oriented in alignment with the relieved portion 73 of the aperture. The control rod 66 is then rotated to interfit the tongue 71 bounding the aperture 72 into the sector groove 70 and the tubular rod 66 may then be projected rearwardly of the file cabinet along the guide rod 68 to shift the slide 53 to a rearmost position adjacent the rear wall 21. This rearward movement of the slide, through the interconnection of the anchor straps 64 with the slats of the upper and lower closure curtains 35, 36 draws the closure curtains along their tracks 31-34 to a position wherein the curtains lie substantially wholly within the horizontal leg portions 42 of the tracks 31-34. In this condition, terminal slats of the curtains 35, 36 are disposed out of the path of movement of the drawers 11-14 and permit free access to the drawers and their contents. Reversal of the above-described procedure will effect return of the curtains 35, 36 to closed position and repositioning of the slide at its forwardmost position immediately behind the intermediate parting plate 26 where, upon manipulation of the dial 52 to relock the lock 48, the bolt 50 will be projected into position behind the keeper block 60 to retain the curtains in closed position.

If desired, the rearwardly opening channel member comprising the channel sides 54 and web 55 may be dispensed with and the slide formed from a single forwardly opening channel member similar to the channel member 53 which opens forwardly to accommodate the combination lock casing 48 therein. In this event, the channel member 53 will correspond to the width of the channel member which was dispensed with, and the aperture 72 designed to cooperate with the control rod 66 will be formed in the rearwardly disposed web of the channel 53.

Figure 6 shows a further alternative arrangement wherein the principles of the above-described embodiment are incorporated, but the specific structure is modified to accommodate a conventional exposed shackle padlock. In this embodiment, the intermediate parting plate 26' is provided with a central vertically elongated rectangular aperture 75 adapted to accommodate a tongue 76 projecting from a vertical plate 77 which conforms to the cross section of the channel formed by the slide-forming channel member 53' having horizontal channel sides 54' extending between the sides 17, 18 of the file cabinet and a forwardly disposed channel web 55' having an aperture 78 through which the tongue 76 is projected. The plate 77 is preferably welded or otherwise rigidly fixed to the slide channel 53' and the tongue 76 is provided with a circular aperture 79 which is located to lie forwardly of the front surface of the intermediate parting plate 26' when the slide 53' is in its forwardmost position to receive the shackle 80 of a shackle padlock 81. Upper and lower closure curtains 35, 36 are anchored to the channel sides 54' of the slide channel 53' in the same manner as described in connection with the embodiment of Figures 1-5. In the embodiment of Figure 6, however, the control rod 66 and associated components are dispensed with and a handle 82 is provided on the uppermost slat 43 of the upper curtain 35 so that the curtains may be directly manipulated to shift the same to and from closed position. It will be understood that due to the disposition of the anchoring straps 64 in a position which will dispose the lowermost and uppermost slats 43 of the upper and lower curtains 35, 36 in vertical alignment with the remainder of the slats when the curtains are in closed position, it will be necessary to manually force these slats

75 rearwardly over a slight portion of the initial movement of the slide, either by directly engaging the slats or by forcing the slide 53' rearwardly by engagement of the tongues 76, in order to relieve the binding action which arises when the slide 53' is in forwardmost position.

While several embodiments of the invention have been shown or described, it is apparent that other modifications may be made in the invention without departing from the spirit and scope thereof, and it is desired, therefore, that only such limitations shall be placed thereon as are imposed by the prior art and are set forth in the appended claims.

We claim:

1. A security closure for valuables and the like, comprising a housing cabinet including an elongated access wall having longitudinally spaced access openings affording admission to the interior of the cabinet interspersed by a medial transverse parting member, shielding means associated with each of said access openings for selectively covering the same to deny admission to said interior comprising a plurality of flexible curtains corresponding to the number of access openings adapted to be shifted into a completely covering relation with said access openings, each opening having a separate curtain associated therewith, slideway means associated with each of said access openings slidably supporting said curtains for movement from a closure position wherein said curtains extend oppositely longitudinally along said access wall from said parting member in covering relation to said openings to a receded position wherein said curtains are withdrawn from said access walls into said cabinet along normals of the medial access wall portion occupied by said parting member for exposing said access openings, a curtain controlling slide member supported for rectilinear reciprocative movement within said cabinet along a plane lying perpendicularly to said parting member and extending inwardly of the cabinet, means positively intercoupling said slide member with both of said curtains for positioning said curtain means in accordance with the position of said slide member, said slide member positioning said curtains in cabinet closing position when said slide member is at one limit position adjacent said parting member and withdrawing said curtains into said receded position upon movement of said slide member away from said parting member, and means associated with said parting member for positively locking said slide member at said limit position to retain said curtains in cabinet closing position.

2. A security closure for valuables and the like, comprising a housing cabinet including an elongated front wall having longitudinally spaced access openings affording admission to the interior of the cabinet interspersed by a medial transverse parting member, shielding means associated with each of said access openings for selectively covering the same to deny admission to said interior comprising a flexible curtain associated with each of said access openings for selectively covering the same, opposed inwardly opening slideway grooves fixed within said cabinet for slidably supporting the curtains associated with said openings, said grooves including groove portions receding within said cabinet along normals of said front wall extending rearwardly of the front wall from a position adjacent said parting member for housing said curtains in said cabinet substantially within the normal projection of said parting member to withdraw said curtains from covering relation with said access openings, and longitudinally spaced groove portions forming a continuous groove with said receding groove portions and extending in opposite directions in a common plane longitudinally of said front wall from said parting member for positioning said curtains in covering relation with said access openings, a curtain controlling slide member supported for rectilinear reciprocative movement within said cabinet within the normal projection of said parting member from one limit position adjacent said parting member

to a rearwardly spaced position remote therefrom, means interconnecting said curtains with said slide member for placing the position of said curtains under control of said slide member, said curtains being disposed in cabinet closing position when said slide member is at said limit position, and means associated with said parting member for locking said slide member at said limit position.

3. In a security file cabinet of the type having a vertical front wall having an even number of vertically aligned drawer openings and horizontally reciprocative drawers supported in said drawer openings for movement normal to said front wall, a marginal frame for said front wall projecting forwardly of the plane of said front wall having a medial transverse parting plate located between the pair of drawer openings adjacent the bisecting axis of said front wall and lying in the plane of said marginal frame to define an upper access opening for the drawers above said bisecting axis and a lower access opening for the drawers below said bisecting axis, upper and lower opposed inwardly opening slideway grooves fixed within said cabinet associated respectively with said upper and lower access openings, said upper grooves having a vertical portion rising from a point adjacent said parting plate within the plane of said marginal frame for the height of said upper access opening and said lower grooves having a vertical portion depending from a point adjacent said parting plate in the plane of said marginal frame for the height of said lower marginal opening, and each of said grooves having a horizontal portion receding from said parting plate in spaced parallel relation with each other and with the normal plane of said parting plate and a curved portion interconnecting said horizontal portions with said vertical portions to form continuous channel slideways, a flexible curtain associated with each of said access openings slidably mounted in said grooves for movement from a vertical cabinet closing position overlying said drawers to a receded position in the curved and horizontal portions of said groove out of the path of movement of said drawers, a slide carriage interconnecting said curtains for coordinating movement of the same under control of said slide carriage, means supporting said slide carriage for reciprocative movement between said horizontal groove portion from a first limit position adjacent said parting plate wherein said curtains are retained in a common vertical plane covering said access openings to a second rearwardly spaced limit position wherein said curtains are withdrawn into receded position, and means cooperating with said parting plate for positively locking said slide carriage at said first limit position.

4. In a security file cabinet of the type having a vertical front wall having an even number of vertically aligned drawer openings and horizontally reciprocative drawers supported in said drawer openings for movement normal to said front wall, a marginal frame for said front wall projecting forwardly of the plane of said front wall having a medial transverse parting plate located between the pair of drawer openings adjacent the bisecting axis of said front wall and lying in the plane of said marginal frame to define an upper access opening for the drawers above said bisecting axis and a lower access opening for the drawers below said bisecting axis, upper and lower opposed inwardly opening slideway grooves fixed within said cabinet associated respectively with said upper and lower access openings, said upper grooves having a vertical portion rising from a point adjacent said parting plate within the plane of said marginal frame for the height of said upper access opening and said lower grooves having a vertical portion depending from a point adjacent said parting plate in the plane of said marginal frame for the height of said lower marginal opening, and each of said grooves having a horizontal portion receding from said parting plate in spaced parallel relation with each other and with the normal plane of said parting plate and a curved portion inter-

connecting said horizontal portions with said vertical portions to form continuous channel slideways, a flexible curtain associated with each of said access openings slidably mounted in said grooves for movement from a vertical cabinet closing position overlying said drawers to a receded position in the curved and horizontal portions of said groove out of the path of movement of said drawers, a slide carriage interconnecting said curtains for coordinating movement of the same under control of said slide carriage, a pair of transversely aligned tracks in said cabinet lying between said horizontal groove portion and extending rearwardly from said parting plate for guiding said carriage, rollers supporting said carriage on said tracks for rectilinear reciprocative movement from a first limit position adjacent said parting plate wherein said curtains are retained in a common vertical plane covering said access openings to a second rearwardly spaced limit position wherein said curtains are withdrawn into receded position, said slide carriage having a keeper thereon, and lock means mounted on said parting plate having a reciprocative bolt projectable into interlock relation with said keeper when said slide carriage is at said first limit position to lock said curtains in cabinet closing position.

5. A security closure for valuables and the like, comprising a housing cabinet including a vertical front access wall having a pair of vertically spaced access openings affording admission to the interior of the cabinet, a parting plate lying in a vertical plane extending transversely across said front wall centrally of the height of said wall, the upper and lower edges of said parting plate forming adjacent bounding walls for said pair of access openings, shielding means associated with each of said access openings for selectively covering the same to deny admission to the interior of the cabinet comprising a flexible curtain associated with each of said access openings for selectively covering the same, curtain guide tracks fixed within said cabinet for slidably supporting said curtains including vertical track portions lying in a common vertical plane extending for the height of their associated access opening and connecting horizontal track portions extending inwardly of the cabinet from a point adjacent said parting plate of a length to accommodate the entire associated curtain within said last mentioned track portion, a lock supported on said parting plate having a lock casing lying inwardly of said parting plate and including a reciprocative bolt projecting parallel to the plane of said parting plate from said lock casing, a pair of horizontally aligned slide tracks fixed within said cabinet and extending rearwardly from said parting plate, a curtain controlling slide carriage supported for rectilinear reciprocative movement within said cabinet on said slide tracks from one limit position immediately adjacent the inner surface of said parting plate to a rearwardly spaced position remote therefrom, said slide carriage comprising a forwardly opening horizontal channel positioned to receive said lock casing in nested relation therein when said carriage occupies said limit position and having a keeper cooperative with said lock bolt for holding said carriage against displacement from said limit position when said lock bolt is projected, means positively interconnecting said curtains with said slide carriage for simultaneously moving said curtains under control of said slide carriage, and control means coupled to said slide carriage and projecting to an exposed position externally of said cabinet for manual shifting of said slide carriage along said slide tracks.
